UNITED STATES PATENT OFFICE.

HAROLD B. HEILMANN, OF NEW YORK, N. Y.

GARMENT.

1,404,855.

Specification of Letters Patent. Patented Jan. 31, 1922.

Application filed July 19, 1920. Serial No. 397,197.

To all whom it may concern:

Be it known that I, HAROLD B. HEILMANN, a citizen of the United States, residing at New York, in the county of New York and State of New York, have invented new and useful Improvements in Garments, of which the following is a specification.

The present invention relates to union garments of that general type now in use and which is characterized by an open front and a partially open back to provide an appropriate seat opening, so that the garment may be conveniently unbuttoned to uncover the buttocks and which, when buttoned, will give a smooth and finished closure.

Broadly considered, this type of garment is old and my improvement is to be regarded as a specific improvement on this generally old type.

My specific improvement has advantages in the matter of convenience and economy in cutting the pieces of which the garment is made; facility in assembling and sewing the pieces together, and advantages in fit and ease of manipulation in the finished garment which distinguish it from anything known to me in the prior art.

In order that the same may be clear to those skilled in the art, I have disclosed in the drawings herewith one physical embodiment of the invention, but it will be understood that this disclosure is illustrative but not restrictive of my invention.

In the drawings:

Figure 1 is a front view of my improved garment.

Figure 2 is a back view with the garment buttoned.

Figure 3 is a back view with the garment unbuttoned.

Figure 4 is a view of one of the front pieces of which the garment is made, the other front piece being identical with this as they are rights and lefts.

Figure 5 is a front view of the upper back piece.

Figure 6 is a view of a leg piece for the back of the leg, this leg piece being the left leg, as shown in Figure 2, in the particular garment here illustrated.

Figure 7 is a view of the back leg piece for the right leg shown in Figure 2.

Figure 8 is a view of the flap and leg piece forming part of the right leg shown in Figure 2.

Referring to the drawings by numbers,

like numbers indicating like parts in the several views, 10 denotes the front piece of the garment which, as shown in Figures 1 and 2, is a single piece made in rights and lefts and provided with suitable fastenings at the central meeting edges, such for example as the buttons and buttonholes shown. At their upper ends, the pieces 10 will be provided with suitable neck yokes and reinforcements and joined on the shoulders with the back piece 11, which, as shown in Figure 5, is preferably cut in a single piece, suitably shaped as to neck and arm holes.

It will be observed that the crotch cuts 12 of the pieces 11 are so made as that in the assembled garment (see Figure 1) the seam joining the crotch edges will be at the front of the leg and not at the inner side of the leg, and furthermore, the crotch is so formed on the front pieces as that its upper end, formed by the meeting edges of the two front pieces 10, is above and in front of the crotch, the back pieces of the legs, which will be hereinafter described, being so shaped as to throw this seam forward and avoid a multiplicity of seams immediately at and below the crotch.

As stated, the back section 11 forms the upper portion of the back of the garment and the lower portion or the leg parts will be formed with respect to one leg (the left leg as shown in Figure 2) from the piece 13 shown in Figure 6, the leg piece 13 being cut so as to give sufficient material at the inside leg edge 14 and the inside crotch edge 15 (see dotted lines in Figure 6), as to permit these edges to be brought forward and joined with the crotch edges 12 in front as shown in Figure 1, instead of at the inside of the leg and directly beneath the crotch, thus eliminating all except the central seam 16 beneath the crotch which joins the crotch edges 15 of the leg piece 13 with the opposite leg.

The other leg of the garment (the right leg as here shown in Figure 2) is preferably formed of two pieces 17 (Fig. 7) and 18 (Fig. 8), the piece 17 being cut at its inside on a curve 19 so as to give, when the pieces are assembled, a rear opening as will appear from Figure 3.

The section 18 is cut so as to form a complementary part 20 for the leg portion 17 and, when assembled, serves to cover the rear opening formed by the piece 17 in its cut away part 19, and the piece 18 further

more has the leg and crotch portion 21 preferably, although not necessarily, formed integral therewith, this leg and crotch portion being given a fullness of cut, as indicated by dotted lines in Figure 8.

The piece 18 will be stitched into a loose waist-band section 22, at its upper end, which waist-band section will also have stitched in it a portion of the leg piece 16. 10 This loose waist-band section 22 will preferably extend only partially across the back, and the leg section 13 and the leg section 17 will, at their upper ends, be stitched into the permanent waist-band 23, as will appear 15 in Figure 3.

The leg section 21 of the piece 18 will, as shown in Figure 2, be stitched down the back of the leg away from the inside and the crotch to the piece 17, so that there will 20 be no inner or crotch seams except that central seam 16 heretofore described, and bunching of seams with the attendant difficulties in sewing and the discomforts incident to a multiplicity of seams at the inside 25 of the legs and the crotch is done away with.

The flap section 20 of the leg section 18 swings over and past the median line of the body and its outer edge lies beyond the point or center of the buttock. With this arrangement, the closure with its fasteners is removed from the seating area of the buttocks and the discomforts incident to a seam or closure traversing that area are avoided. Furthermore, the closure line is at a point 35 removed from the line of strain, so that gaping and opening of the closure is avoided.

The covering flap is so disposed as that but few fastenings are necessary, one as shown at the waist-band and the other at 40 substantially the top of the curve in the flap, and these are so positioned that they may be readily manipulated in releasing and closing the flap.

It will be observed that with this closure, 45 all outside seam openings are done away with and the garment as viewed from either side is completely closed as to its side seams. The back closure is of such construction that it gives a properly positioned and proportioned opening when unfastened, without the necessity of a loose side flap of any great area and without unduly extending the loose waist band portion.

It will be understood, of course, that variations in design may be made to a considerable extent without departing from my invention and that while I have disclosed herein the cuttings of pieces of what I believe to be the best and most economical 55 form, they might, of course, be cut into several component parts without departing from my invention. For example, the piece 18 might be formed in two parts with the leg section 21 one piece and the flap section 20 in another piece, and such variations 60

as these are deemed to be within the range of my invention.

I claim:

1. A union garment comprising front body and leg portions and having a body 70 opening to permit putting on of the garment, the leg portions being cut at their inner sides to bring their edges forwardly from the inner sides of the legs and above the crotch, a back comprising body and leg 75 portions, one of which leg portions is closed and has its inner side extended to project forwardly past the inside of the leg and above the crotch to the cut back edge of the same leg front portion, and the other leg portion has 80 a seat opening and is cut away at the inside of the leg so as not to extend directly to the front leg portion for the same leg, a closing flap for said opening secured to the inner edge of the closed leg portion, said 85 flap being free at its top and curved outwardly from its top and then inwardly to the inner side of the leg portion having the opening, and a leg section at the lower end of said closing flap extending down the inside 90 of the leg, said flap leg-section extending forwardly past the inside of the leg and above the crotch to the cut back edge of the same leg front portion and extending rearwardly to the inner edge of the back leg 95 portion to which it is joined by a line of stitching extending from a point at the base of the right buttock to the lower end of the same leg portion, said opening covered by the flap terminating at the top of said line 100 of stitching.

2. A union garment comprising front body and leg portions and having a body opening to permit putting on of the garment, the leg portions being cut at their inner sides to bring their edges forwardly away from the inner sides of the legs and above the crotch, a back comprising body and leg portions, one of which leg portions has a seat opening and the other leg portion has its inner side extended to project forwardly past the inside of the leg and above the crotch to the cut back edge of the same leg portion, the leg portion having the opening being cut away at the inside of the 110 leg so as not to extend directly to the front leg portion for the same leg, a closing flap for said opening secured to the inner edge of the other leg portion, said flap being free at its top and curved outwardly from its top 115 and then inwardly to the inner side of the leg portion having the opening, and an integral leg section at the lower end of said closing flap extending down the inside of the leg, said flap leg section extending forwardly 120 past the inside of the leg and above the crotch to the cut back edge of the same leg front portion and extending rearwardly to the back of the leg at the inner edge of the 125 back leg portion to which it is joined by a 130

line of stitching extending from a point at the base of the right buttock to the lower end of the same leg portion, said opening covered by the flap terminating at the top of 5 said line of stitching.

3. A union garment having a permanently closed crotch and provided with a leg portion cut away to form a seat opening extending from the waist line at substantially 10 a medial point to a point just below one buttock, and a closing flap for said opening having a free outer edge adapted to be detachably secured to the garment, said

free outer edge terminating at the inner side of the back of the leg, the back portion 15 of the leg having the opening being at the inside of the leg cut away so as not to extend across the inside of the leg to the same leg front portion, and a leg section at the lower end of said closing flap permanently 20 stitched into the inside of the said leg and extending from the crotch to the bottom of the leg.

In testimony whereof I have hereunto set my hand.

HAROLD B. HEILMANN.
